UNITED STATES PATENT OFFICE.

JAMES MARLBOROUGH, OF TOPSFIELD, MASSACHUSETTS.

FOUNTAIN-PEN.

1,130,622.

Specification of Letters Patent.

Patented Mar. 2, 1915.

Application filed April 7, 1914. Serial No. 930,252.

To all whom it may concern:

Be it known that I, JAMES MARLBOROUGH, a citizen of the United States, residing at Topsfield, in the county of Essex and State 5 of Massachusetts, have invented new and useful Improvements in Fountain-Pens, of which the following is a specification.

The invention relates to fountain pens, and has for an object to provide a fountain 10 pen of a simple construction and which is so arranged and constructed that it will not leak when carried in the pocket and when not in use.

The invention contemplates, among other 15 features, the provision of a fountain pen having suitable means within the control of the user whereby the supply of ink to the nib can be shut off when the fountain pen is not in use and carried in the pocket and 20 whereby such supply of ink to the nib will be uninterrupted when the pen is in use.

In the further disclosure of the invention reference is to be had to the accompanying drawings, constituting a part of this specification, in which similar characters of reference denote corresponding parts in all the views, and in which:

Figure 1 is a perspective view of the pen; Fig. 2 is a fragmentary vertical longitudinal 30 sectional view; Fig. 3 is a vertical transverse sectional view; Fig. 4 is a perspective view of the valve; and Fig. 5 is a view looking at the under side of the slide. Fig. 6 is a fragmentary plan view of the structure shown 35 in Fig. 1, with the slide member removed.

Referring more particularly to the views, I provide a pen 10 consisting, more particularly, of a barrel 11 and a nib-supporting member 12 adapted for threaded engagement with the barrel 11 and carrying the usual nib 13. The nib-supporting member 12 is provided with a longitudinal passage 14, through which the ink is adapted to flow in passing from the barrel 11 to the nib 13. 40 Mounted to turn in the nib-supporting member 12 is a frusto-conical valve 15 provided with a horizontal passage 16 and which, by turning the valve 15 in the nib-supporting member 12, can be moved into or 45 out of registration with the passage 14, said valve 15 being so arranged as to interrupt the passage 14 when it is desired to cut off the supply of ink from the barrel to the nib. The nib-supporting member 12 is provided 50 with a recess 17 closed at one end and terminating at the other end adjacent that portion 55 of the nib-supporting member which is adapted for threaded engagement with the barrel 11. Mounted to slide in the said recess is a slide member 18, the said slide member preferably having its sides 19 beveled to conform to oppositely inclined walls 20 of the recess 17 so that when the slide member 18 is arranged in the recess the same cannot be removed except by sliding it out 60 of the open end of the recess. A slot 21 is formed in the under side of the slide member 18 and is adapted to receive therein a bead 22 formed on a stem 23 of the valve 15 so that in moving the slide member 18 forwardly and backwardly in the recess 17, rotation will be imparted to the valve 15 to move the passage 16 into or out of registration with the passage 14 in the nib-supporting member 12. A bead 24 is preferably 65 formed at the forward end of the barrel 11 and when the nib-supporting member 12 is threadedly engaged with the barrel 11, the said bead will constitute a stop member to limit the sliding movement of the slide member 18 in the recess 17 so that in order to remove the slide member 18 from the recess it will be first necessary to unscrew the nib-supporting member 12 from the barrel 11. 70 Now it will be apparent that when the slide member 18 is moved forwardly in the recess 17 it will impart rotation to the valve 15 to register the passage 16 with the passage 14 so that the ink can flow from the barrel to the nib, whereas when the slide member is 75 retreated in the recess the valve will be rotated in the opposite direction to move the passage 16 out of registration with the passage 14, thus cutting off the supply of ink from the barrel to the nib. In order to prevent mistakes by the user, the letters "S" and "O" indicating, respectively, "Stopped" 80 and "Open," are stamped or otherwise formed in the floor or bottom of the recess 17 as shown so that when the letter "S" is 85 uncovered the slide member will be in its rearmost position, thus through the medium of the valve stopping the flow of ink from the barrel to the nib, whereas when the slide is in its forward position the letter "S" 90 is 100 uncovered the slide member will be in its rearmost position, thus through the medium of the valve stopping the flow of ink from the barrel to the nib, whereas when the slide is in its forward position the letter "S" 105 will be covered and the letter "O" uncovered and in position to indicate that the valve is in a position to register the passages 14 and 16 so that the ink can flow from the barrel to the nib.

The slide member 18 is preferably made of resilient sheet metal or the like so that

in initially placing the same in the recess 17 the same is sprung into the recess and in order to insure the engagement of the slide member with the valve so that the same can 5 be relatively operated and it will be apparent that when the slide member has once been sprung into the recess it will be almost impossible to conveniently remove the same unless the slide member is slid outwardly 10 through the open end of the recess. This, however, would be impossible in view of the beveled sides of the slide member and the fact that the bead 22 of the valve extends into the transverse slot 21 in the under side 15 of the slide member. The bead 24 on the forward end of the barrel, however, will tend to limit the sliding movement of the slide member in the recess, as will be readily understood by referring to the views.

20 Having thus described my invention, I claim:

1. In a fountain pen, the combination with a barrel, of a nib-supporting member for threaded engagement with the barrel 25 and provided with a recess and a longitudinal passage, a nib carried by the nib-supporting member, said passage being adapted to convey ink from the barrel to the said nib, a valve mounted to turn in the said nib- 30 supporting member and provided with a passage which can be moved into or out of registration with the passage in the nib-supporting member, a slide member mounted to slide in the recess in the said nib- 35 supporting member, and means projecting from the said valve and coöperating with the slide member for operating the said valve to move its passage into or out of registration with the passage in the nib-sup- 40 porting member when the said slide member is actuated.

2. In a fountain pen, the combination with a barrel, of a nib-supporting member for threaded engagement with the barrel 45 and provided with a recess and a longitudi-

nal passage, a nib carried by the nib-supporting member, said passage being adapted to convey ink from the barrel to the said nib, a valve mounted to turn in the said nib-supporting member and provided with a 50 passage which can be moved into or out of registration with the passage in the nib-supporting member, a slide member mounted to slide in the recess in the said nib-supporting member, means projecting from the said valve and coöperating with the slide member for operating the said valve to move its passage into or out of registration with the passage in the nib-supporting member, and a bead formed on the forward 55 end of the barrel and engaged by the said slide member when the nib-supporting member is attached to the barrel, to limit the movement of the slide member in the said recess. 65

3. In a pen, the combination with a barrel, of a nib-supporting member for connection therewith, said nib-supporting member having a longitudinal passage communicating with the barrel, a valve mounted to 70 turn on the said nib-supporting member to interrupt the said passage, a stem on the valve, a bead projecting from the stem and extending into a recess in the said nib-supporting member, a slide member in the said 75 recess and adapted to be moved forward and backward therein, and a slot formed in the under side of the slide member and into which the bead of the said stem extends whereby, when the slide member is advanced or retreated in the said recess, the 80 said valve will be actuated to open or close the passage in the said nib-supporting member.

In testimony whereof I affix my signature in presence of two witnesses.

JAMES MARLBOROUGH.
